UNITED STATES PATENT OFFICE.

PERCY C. SMITH, OF CHICAGO, ILLINOIS, ASSIGNOR TO JOHN F. MEYER, OF CHICAGO, ILLINOIS.

STEREOSCOPIC EXHIBITING MACHINE.

Application filed August 29, 1927. Serial No. 216,014.

This invention relates to stereoscopic exhibiting machines and particularly to automatic operating mechanism therefor; and to coin safety mechanism for controlling the 5 operating mechanism.

The objects of the invention are to provide a device for exhibiting machines which will rotate a card holding reel adapted, in this instance, to carry five different series of 10 photographic cards of the stereoscopic type; which will automatically operate the card holding reel by means of a spring motor automatically controlled by a coin; and which will stop the motor after one-fifth of a revolution of the reel and show one series of pictures during that part revolution.

Another object is to provide novel and improved means for automatically starting the reel in motion upon the insertion of a coin, 20 and which will automatically stop after one series of picture cards has been shown.

And a further object is to provide improved safety means for controlling the operation of the machine so that only one series of cards can be shown for the one coin, 25 and which will prevent interruption of the controlling mechanism during the operation of the reel.

In the accompanying drawings which is a 30 selected embodiment of the invention the views are as follows:

Fig. 1 is a vertical sectional view showing the operating mechanism and the means for controlling the operating mechanism.

Fig. 2 is a transverse sectional view of the 35 parts shown in Fig. 1.

Fig. 3 is a detail top plan view of my machine with the cover removed.

Fig. 4 is a detail perspective view showing 40 the controlling mechanism tripping position.

Fig. 5 is a similar view showing the mechanism after it has been tripped.

Fig. 6 is a similar view showing the safety 45 mechanism upon its return movement.

Referring to the drawings 1 designates the casing of the machine supporting the drive shaft 2 which is driven by the spring 3 through the chain of gears 4.

50 A flat vertical operating rod 5 is loosely connected to the plate 6 arranged within the casing and has a slot 7 through which the screw 8 extends. A bracket 9 connected to the plate forms a guide for the rod 5 which

is free to move vertically through a slot 10 55 (Fig. 3) in the top of the casing. The vertical movement of this rod is restricted by the size of the slot 7 but is free to move laterally a slight distance and is held against the inner side of the bracket 9 by a light tension 60 spring 11.

An angular stop lever 12 pivoted to the plate 6 at 13 is free to engage the uppermost of a plurality of notches 14 in the circular disk 15 fixed to the shaft 2. The end 16 of 65 the stop lever 12 engages the governor 17 when the stop lever engages the uppermost notch 14. By providing a plurality of notches 14 in the disc 15 as shown I am able to stop the machine five times during each 70 revolution of the wheel which enables me to show five different series of pictures. A pin 18 projecting from the rod 5 is adapted to engage with the stop lever 12 so that when the rod 5 is moved downward the pin 18 75 will bear against the upper edge of the stop lever and cause that lever to recede from the notch 14 and at the same time cause the end 16 of the stop lever to raise upwardly and allow free movement of the governor 17. 80

A horizontal return rod 19 pivoted to the plate 6 has its outer end 20, Fig. 2, arranged near the wheel 15 and is adapted to be engaged successively by the pins 21 projecting outwardly from the disk 15. 85

This rod is bent outwardly at 22 so that during the rotation of the disk 15 the pins 21 will be normally free from the end 20 of the rod 19, as will be later apparent. The end 23 of the rod is bent outwardly and is 90 free to contact with a bracket 24 on the lower end of the rod 5. The purpose of the rod 19 is to return the rod 5 upwardly to normal position after it has been lowered in starting. When the machine is in motion 95 and the disk 15 is rotating the pins 21 will contact with the end 20 of the rod 19 and push it downward thus raising the end 23 thereof and causing the rod 5 to rise back to normal or starting position. The disk 15 will continue to rotate even after the lever 5 is raised and until the lever 12 engages the uppermost one of the notches 14. After the rod 5 is returned to normal and the disk 15 is still rotating, the pins 21 will be free of the rod 19 and will ride under the bent portion 22.

A spring clip 25 is fastened to the rod 5

and abuts against a pin 26 on the plate 6. This pin prevents the rod 5 from falling downward of its own accord and locks the rod 5 in its normal or raised position.

5 A spring finger 27 is fastened to the end of an actuator, or coin slide 28 which is preferably the slide shown and described in Patent No. 1,592,285, July 13, 1926, owned by my assignee. This finger engages the upper end of the rod 5, Fig. 4, when a coin is inserted in the slide to start the machine and a spring arm 29 fastened to the top of the casing causes the finger 27 to pass under it on the inward movement of the finger to 10 start the machine but rides over the arm 29 upon the outward or return movement of the finger.

The operation of the device is as follows: When a coin is inserted in the coin slide 28 20 and the slide is pushed inwardly it carries the spring finger 27 with it. The finger 27 will ride under the arm 29 and push the rod 5 to the left, Figs. 1 and 3, until the spring clip 25 on the rod 5 is moved off the pin 26 when the spring 11 will pull the rod 5 downward causing the pin 18 to press down on the left end of the lever 12, Fig. 1, and raise this lever out of the top notch 14 and also to raise the end 16 away from 30 the governor 17 thus allowing the machine to operate. During the downward movement of the rod 5 the bracket 24 will press against the end 23 of the rod 19 to raise the end 20 of the rod 19 into position to be 35 engaged by one of the pins 21. As the disk 15 rotates the pins 21 cause the end 20 of the rod 19 to be lowered thereby raising the end 23 to move the rod 5 upwardly until the spring clip 25 is again seated on the pin 26. 40 The disk 15 will continue to rotate until the lever 12 engages the uppermost notch 14 to stop further rotation thereof. Simultaneously with the engagement of the lever 12 with the top notch 14 the end 16 of the lever 12 will contact with the governor 17 providing an additional or double stop. The spring clip 25 has sufficient elasticity or 45 springiness so that when the rod 5 raises, the clip will give and allow it to pass over the pin 26 and again be seated on the pin 26. The finger 27 passes over the arm 29 during the return or outward movement of the coin slide 28 as designated by the arrow in Fig. 6. This arrangement keeps the finger 55 from hindering the upward movement of the rod 5 in any way. It also provides means whereby it is impossible to have the machine operate again without inserting another coin, as the clip can in no way again move the rod 5 until the slide 28 is pulled back and another coin inserted. However the finger 27 has sufficient elasticity, that should the operator fail to withdraw the coin slide 28 after pushing it inwardly, the 60 rod may still rise by deflecting the spring

finger sufficiently to allow the rod 5 to rise to normal position. This deflection however is very slight as the arm 29 causes the finger 27 to be raised or sprung away from the upper end of the rod 5. The coin slide forms no part of my present invention but is mentioned for the sake of clarifying the operation of the parts. A second governor 70 30 may be fixed to one of the gear shafts to assure steadiness of operation and by bending or crimping the blades thereof the speed of the axle 2 may be increased or decreased as desired. 75

The present machine embodying my invention is particularly adapted to operate a reel such as is disclosed and claimed in my companion application, Ser. No. 216,013, filed concurrently herewith. I make provision for carrying the reel by arranging a socket 31 on the disk 15 for the accommodation of the axle of the reel, although the machine is adapted to accommodate any other reel of a similar construction or character.

Changes may be made in the form, construction and arrangement of the parts without departing from the spirit of the invention or sacrificing any of its advantages and I hereby reserve the right to make all such changes as fairly fall within the scope 95 of the following claims:

I claim:

1. An automatic stereoscopic exhibiting machine comprising a casing, a shaft arranged in said casing, a circular disk having 100 peripheral notches fixed to said shaft, means to rotate said shaft and an angular lever adapted to engage said notches successively to stop the rotation of said shaft, means for disengaging the lever from a notch, and means controlled by the disc for restoring the lever for engagement with the next succeeding notch.

2. An automatic stereoscopic exhibiting machine comprising a casing, a shaft arranged in said casing, a circular disk having peripheral notches fixed to said shaft, means to rotate said shaft, means arranged on said disk to accommodate a reel, and an angular lever adapted to engage said 110 notches successively to stop the rotation of said shaft, means for disengaging the lever from a notch, and means controlled by the disc for restoring the lever for engagement with the next succeeding notch.

3. An automatic stereoscopic exhibiting machine comprising a casing, a shaft arranged in said casing, a circular disk having peripheral notches fixed to said shaft, means to rotate said shaft, means arranged 125 on said disk to accommodate a reel, an angular lever adapted to engage said notches successively to stop the rotation of said shaft, and a rod for operating said lever to raise said lever from one of the notches.

4. An automatic stereoscopic exhibiting machine comprising a casing, a shaft arranged in said casing, a circular disk having peripheral notches fixed to said shaft, means to rotate said shaft, means arranged on said disk to accommodate a reel, an angular lever adapted to engage said notches successively to stop the rotation of said shaft, a rod for operating said lever to raise said lever from one of the notches, pins on said disk, a horizontal rod cooperating with said first named rod and adapted to be successively engaged by said pins to raise said first named rod to starting position. 65
5. An automatic stereoscopic exhibiting machine comprising a casing, a shaft arranged in said casing, a circular disk having peripheral notches fixed to said shaft, means to rotate said shaft, means arranged on said disk to accommodate a reel, an stop lever adapted to engage said notches successively to stop the rotation of said shaft, a rod for operating said stop lever to raise said lever from said notches, pins on said disk, a return rod cooperating with said first named rod and adapted to be successively engaged by said pins to return said first named rod to starting position, means arranged on said casing to allow lateral movement of said operating rod, and a spring for causing said operating rod to be pulled downwardly to operate said lever. 70
6. In combination, a rotatable disk having peripheral notches, a stop lever adapted to engage said notches successively during rotation of said disk to stop the same, pins on said disk, an operating rod for operating said stop lever, and a return rod operated by said operating rod and engaging said pins whereby said return rod will raise said operating rod back to starting position during rotation of said disk. 75
7. In combination, a rotatable disk having peripheral notches, a stop lever adapted to engage said notches successively during rotation of said disk to stop the same, pins on said disk, an operating rod for operating said stop lever, a return rod operated by said operating rod and engaging said pins whereby said return rod will raise said operating rod back to starting position during rotation of said disk, a spring clip on said operating rod, and a pin for engaging the end of said clip to hold the operating rod in starting or normal position. 80
8. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, an actuator, and means connected to said actuator for operating said operating rod. 85
9. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, a slide, and a spring finger on said slide for operating said operating rod when said slide is moved inwardly. 90
10. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, a slide, a spring finger on said slide for operating said operating rod when said slide is moved inwardly, and a spring arm arranged on said casing for guiding said finger and to raise said finger upon return movement of said slide whereby said finger is prevented from operating said vertical rod unless the slide is again operated. 95
11. In combination with a rotatable disk having means for engaging said disk to stop the same, of an operating rod for controlling the operation of said means, a pin, a spring clip on said rod and adapted to engage said pin to hold the rod in position, means for allowing lateral movement of said rod for causing the clip to be released from the pin, and spring means for causing said rod to be pulled downwardly to operate said first named means. 100
12. In combination with a rotatable disk having means for engaging said disk to stop the same, of an operating rod for controlling the operation of said means, a pin, a spring clip on said rod and adapted to engage said pin to hold the rod in position, an actuator, a spring finger on said actuator and adapted to move said rod laterally to cause said clip to be released from said pin, spring means for pulling the rod downwardly to operate said first named means, and a spring arm for causing the finger to be moved away from said rod during operation of the machine, whereby said rod cannot again be operated without repeat operation of the actuator. 105
13. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, an actuator, and means connected to said actuator for operating said operating rod. 110
14. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, a slide, and a spring finger on said slide for operating said operating rod when said slide is moved inwardly. 115
15. In combination a casing, a rotatable disk having peripheral notches, a stop lever for engaging said notches successively to stop said disk, an operating rod for operating said stop lever, a return rod for returning said operating rod to starting position, a pin on said casing, a spring clip on said operating rod for engaging said pin to hold the operating rod in starting position, an actuator, and means connected to said actuator for operating said operating rod. 120

PERCY C. SMITH.
